CLAIM

The ornamental design for a receptacle cover, as shown and described.

DESCRIPTION

FIG. 1 is an outside plan view of a receptacle cover showing my new design;

FIG. 2 is a bottom side view thereof, the top side view being a mirror image thereof;

FIG. 3 is a left side view thereof, the right side view being a mirror image thereof;

FIG. 4 is an inside plan view thereof;

FIG. 5 is a side view thereof in cross section; and,

FIG. 6 is a cross section taken along the plane of 6-6 in FIG. 4.

The broken lines in FIGS. 1 and 4 denote that the receptacle cover is of indeterminate width. The broken lines in FIG. 5 illustrate the receptacle cover in use with a cover plate and duplex receptacle. The receptacle cover is lined for transparent material with paint on the inside.
